UNITED STATES PATENT OFFICE

99,655

DESIGN FOR A COMBINED BOOKCASE, RADIO, STATIONERY COMPARTMENT, LIQUOR COMPARTMENT, CLOCK AND LAMP, OR SIMILAR ARTICLE

Napoléon H. Boisvert, Cambridge, Mass.

Application February 10, 1936, Serial No. 61,062

Term of patent 7 years

To the Commissioner of Patents:

Be it known that I, Napoléon H. Boisvert, a citizen of the United States of America, residing at Cambridge, in the county of Middlesex and Commonwealth of Massachusetts, have invented a new, original, and ornamental Design for a Combined Bookcase, Radio, Stationery Compartment, Liquor Compartment, Clock and Lamp, or Similar Article, of which the following is a specification, reference being had to the accompanying drawing, forming part thereof.

Figure 1 is a front elevation view of a combined

bookcase, radio, stationery compartment, liquor compartment, clock and lamp embodying my new design.

Figure 2 is a side elevational view of the same, both sides being substantially the same.

The rear is substantially plain.

I claim:

The ornamental design for a combined bookcase, radio, stationery compartment, liquor compartment, clock and lamp or similar article substantially as shown and described.

NAPOLÉON H. BOISVERT.
